BUTTON BLANK FEEDER

Joseph C. Worst, Muscatine, Iowa

Application October 25, 1955, Serial No. 542,587

16 Claims. (Cl. 221—236)

This invention relates to button blank finishing machines, preferably those of the well-known Barry type having an endless series of button-blank-holding chucks which move in an orbital path in the machine, said path having at one point a feeding station into which the blanks are inserted into the chucks as they pass the feeding station, and carry the blanks around to other stations which grind, polish or drill the blanks and discharge the blanks from the chucks before the chucks return in their orbital path to the feeding station.

My present invention is a novel means for feeding button blanks, either of plain or shank type, into the moving chucks at the feeding station, said feeding means being adapted to blanks which are either plain or of flat type, or have integral shanks.

One object of the invention is to provide feeding means of the above type having a safety mechanism in the feeding means which will eliminate damage to the buttons or breakage of machine parts in event the blanks in the feeding means should become jammed.

Another object of the invention is to provide a feeding means of the above type in which the feed will be properly resumed after a jam is released, without any adjustment of the parts of the feeding means.

Another object of my invention is to provide a feeding means of the above type in which the feed into the open chucks is always in alignment with the orbital path of the moving chucks during said feeding operation.

A further object of the invention is to provide a feeding means of the above type which, in the event of a button jam in the feeding means, will not feed any blanks at all, thereby eliminating improper feeding, or wasteful spillage of the blanks on the factory floor.

A still further object of the invention is to provide a simple and efficient feeding means having provisions whereby it is impossible to feed more than one button blank at a time into the open chucks, and having means to eliminate the slipping of clutches or breakage of machine parts if a feeding stroke is impeded for any reason, the feeding means automatically resuming feeding in perfect register with the moving chucks after any impeding blank is removed from the path of the fed blanks, without any machine adjustment.

Other minor objects of the invention will be hereinafter set forth.

I will explain the invention with reference to the accompanying drawings which illustrate one practical embodiment thereof, to enable others familiar with the art to adopt and use the same; and will summarize in the claims, the novel features of construction, and novel combinations of parts, for which protection is desired.

In said drawings:

Fig. 1 is a top plan view, partly in section, of a conventional button grinding and finishing machine of the Barry type, showing my novel feeding means disposed at the feeding station.

Fig. 2 is an enlarged plan view of said feeding means, and shewing a row of chucks and the adjacent parts of

2

the Barry machine; and showing the pivot arm of the feeding means engaged with one of the button-blank holding chucks of the Barry machine; also showing a row of button blanks being fed successively into feeding position.

Fig. 3 is a side elevation of a row of chucks of the Barry machine, and showing my novel feeding mechanism; also showing the cam which supports the chucks in the Barry machine and raises or lowers the chucks to open or close same respectively.

Fig. 4 is an enlarged plan view on the line 4—4, Fig. 3.

Fig. 5 is a vertical section on the line 5—5, Fig. 2.

Fig. 6 is an enlarged vertical section on the line 6—6, Fig. 2.

Fig. 7 is an enlarged detail section, showing the feeding finger, and showing a row of button-holding chucks disposed thereunder.

Fig. 8 is an enlarged sectional view showing the location of the sliding pin which initially holds the button blanks in feeding position in the feeding finger prior to being dropped into the open chucks.

Fig. 9 is an enlarged detail view of one of the button blanks initially received in the feeding finger prior to being dropped into the underlying open chucks.

Fig. 10 is a view similar to Fig. 9 but showing the feeding finger shifted into position to drop the button blank into the underlying open chuck as the feeding finger approaches the outward limit of its feeding stroke.

Fig. 11 is a section on the line 11—11, Fig. 9.

Fig. 12 is a section on the line 12—12, Fig. 10.

The button-blank grinding, polishing or drilling machine illustrated in the drawings is of the conventional type commonly known as a Barry blank finishing machine; and consists of a row of chuck spindles A which are pivotally linked together as at B to form an endless series adapted to run around notched discs or wheels C and D respectively mounted on upright shafts E and F, Fig. 1, one of which discs or wheels may be a driving wheel so as to move the endless series of chuck spindles in an orbital path, as indicated by the arrows in Fig. 1. In each of the chuck spindles A is a chuck G having expandable and contractable jaws at its upper end, the chucks G being supported upon ball feet H, Fig. 3, which adjust the chucks G vertically in their respective spindles A, said ball feet H engaging a cam J, Fig. 3, and riding upon the upper surface thereof, said cam J at the feeding station having an upwardly inclined portion J' so that when the ball feet H ride upwardly on the inclined portion J', the fingers of the chucks G above the spindles A will be expanded to permit placement or discharging of a button blank L from the chucks G; but when the ball feet H ride upon the lower horizontal portion of cam J' the chuck fingers will be contracted around the button blanks L and hold same securely in the chucks G while the chucks G pass through the grinding, polishing or drilling stations (not shown). As soon as the button blanks L have been placed in the expanded chucks G, cam J is inclined downwardly immediately beyond the feeding station to contract and securely hold the blanks L in the chucks G. The above arrangement of ball feet H and cam J in said Barry machine is well known in the art, and needs no further description herein; nor does same form any part of my present invention.

My novel automatic button-blank feeding means consists of a feed plate 1 of sufficient size to overlie the orbital path of the chucks G at the feeding station, said feed plate 1 being supported upon a horizontal arm 2 which is mounted on a clamp 3 surrounding one of the vertical frame members K of the Barry machine so as to be securely held in horizontal fixed relation. Preferably plate 1 is provided with transverse slots 4, Fig. 2, engaged by screws 5 or the like on arm 2 which may be loosened

so as to permit feed plate 1 to be adjusted towards or from the orbital path of the row of chucks G at the feeding station so as to align the feeding finger (hereinafter described) with the axial movement of said row of chucks, after which the screws 5 may be tightened to retain feed plate 1 in desired position.

Preferably feed plate 1 and arm 2 are provided with an adjustment assembly 6 to assist in properly holding and adjusting feed plate 1 on arm 2, said adjustment assembly being of any desired type, but as shown comprising a threaded bolt 6a rotatably mounted in a clip 6b on the outer edge of arm 2, bolt 6a being held in clip 6b against axial movement with respect thereto, and the threaded end of bolt 6a engaging a threaded ear 6c on the outer edge of feed plate 1 so that as the bolt 6a is rotated in either direction plate 1 will be shifted transversely of the arm 2.

On the rear end of feed plate 1 are spaced strips 7 and 8 (Fig. 6) respectively, which are disposed at opposite sides of the axis of the orbital path of the row of chucks G, said strips 7—8 being of height greater than the thickness of the button blanks L whether plain or of shank type. Mounted upon the spaced blocks 7 and 8 is a fixed plate 9 which is disposed parallel with and above feed plate 1 between the blocks 7 and 8. Between the plates 1 and 9 is slidably mounted a feeding finger 10 adapted to be reciprocated coaxially with the axis of movement of the row of chucks G, as hereinafter explained, the movement of the feeding finger 10 being limited by a screw 10a on feeding finger 10 which slides in a slot 9a in plate 9, as shown in Figs. 1, 2, 7, 9 and 10.

Sloping downwardly upon feed plate 1 is a feed chute 11 in the form of a guide in which the button blanks L slide by gravity or the like, the lowermost blank L extending through a lateral opening in block 8 and being disposed upon the top surface of feed plate 1. Plate 9, as shown in Fig. 2, has a lateral slot 9b therein whereby the button blanks L from feed chute 11 may slide into a substantially semi-circular recess 10b in feeding finger 10, as clearly shown in Figs. 4, 11 and 12, the button blanks L being fed by gravity into such position.

The longitudinal axis of semi-circular recess 10b of feeding finger 10 is coaxial with the axis of movement of the underlying row of chucks G, and the parts are so arranged that the lowermost button blank L will be adapted to be seated in the underlying chuck G upon the next reciprocation of feeding finger 10.

In order that the row of chucks G underlying the feed plate 1 may be permitted to rise by action of the cam portion J' without striking the underside of feed plate 1, a groove 1x is preferably provided in the underside of plate 1, same being of greater width than the upper ends of the chuck G, as shown in Fig. 6, so that when the ball feet H ride up the inclined portion J' of cam J the tops of the chucks G will not strike the under side of feed plate 1.

Also in feed plate 1, above the axis of movement of the row of chucks G, a slot 1y (Figs. 4 and 11) is provided of narrower width than the diameter of the button blanks L, in which the integral shanks of shank-type button blanks L may drop during the step of feeding the blanks into the opened chucks G.

The width of the feeding finger 10 and the location of the substantially semi-circular recess 10b is such that when the lowermost button blank L from chute 11 has been deposited in the recess 10b prior to being fed into chuck G, that when the feeding finger 10 is shifted to the right (Fig. 4), the side of the feeding finger 10 will engage the next adjacent button blank L, as shown in Figs. 11 and 12, and hold the row of button blanks L in the feed chute 11 from further movement towards feeding finger 10.

In order to prevent the lowermost button blank L which is engaged in the semi-circular recess 10b of feeding finger 10 from being forced out of the semi-circular recess 10b, a pin 12 is provided which is mounted upon a

leaf-spring 13 which, as shown in Fig. 6, lies within a recess formed between block 7 and the adjacent side of the feeding finger 10, which spring 13 when the feeding finger 10 is retracted to the left (Fig. 11) is confined between block 7 and the adjacent face of feeding finger 10 so that the pin 12 will pass through a bore 10x in feeding finger 10 and its outer end will lie in the path of the button blank L which is seated in recess 10b of feeding finger 10; but when the feeding finger 10 is shifted to the right into feeding position as shown in Fig. 12, leaf-spring 13 will spring away from the adjacent edge of feeding finger 10 and will thereby withdraw pin 12 outwardly from bore 10x, thereby permitting the button blank L which is engaged in recess 10b of feeding finger 10 to move axially of the feeding finger 10 into position to overlie and drop into the opened chuck G which underlies the blank L at that instant, as clearly shown in Fig. 12; however, when the feeding finger 10 is again drawn to the left (Fig. 11) the spring 13 and pin 12 will assume the positions shown in Fig. 11 and prevent the next or following button blank L from moving to the right (Fig. 11) out of engagement with the recess 10b of feeding finger 10.

Means are provided for reciprocating feeding finger 10. As shown, the arm 2 carries a pair of transverse guide brackets 16 secured thereto in any desired manner, in which is mounted a travel arm 17 (Figs. 1, 2, 3 and 5) which is adapted to be reciprocated, as hereinafter described, parallel with the orbital movement of the row of chucks G at the feeding station. At the front inner corner of travel arm 17 is a pivot arm 18 (Figs. 1 and 2) pivoted thereto on pin 19, a spring 20 (Fig. 2) normally urging the pivot arm 18 to swing outwardly of the axis of movement of travel arm 17 so that the outer free end of pivot arm 18, as shown in Figs. 1, 2, 4 and 11, will contact the front of a chuck spindle A so as to shift the travel arm 17 to the right (Fig. 2) by and with the movement of the contacted chuck A for a short intermittent travel. A spring 21 has one end fixed to a post on one bracket 16 and its opposite end fixed to a pin on travel arm 17, the spring 21 normally urging the travel arm 17 into retracted position, i. e., movement towards the left (Fig. 2).

In order to release pivot arm 18 from engagement with the chuck spindle A with which it has been engaged, a dog 22 is provided on clamp bracket 3 which is fixed with respect to the Barry machine frame and is inclined outwardly and inwardly with respect to the movement of travel arm 17 so that when the travel arm 17 is moved by pivot arm 18, which is engaged with the related chuck spindle A, and the forward end of pivot arm 18 engages the dog 22 (Fig. 2) the pivot arm 18 will be shifted by such engagement so as to swing the pivot arm 18 towards the travel arm 17 and thereby release the pivot arm 18 from engagement with the chuck spindle A, the pivot arm 18 normally being projected away from the travel arm 17 by action of spring 20.

In order to prevent the pivot arm 18 from swinging outwardly from travel arm 17 an excess distance, a guide rod 25 (Figs. 2, 4, 5 and 12) is provided which is secured to the outer end of pivot arm 18 and which is adapted to contact the adjacent side of the chuck spindle A, as clearly shown in Figs. 2 and 4, to maintain the pivot arm 18 in proper engaged position with the said chuck spindle A.

In order to prevent jamming of the machine and damage to the parts thereof or to the button blanks in event the feed chute 11 should become jammed in any way with blanks L, relief means are provided, as shown in Figs. 1, 2 and 3.

As shown in Fig. 2, the trailing end of travel arm 17 carries a pivoted arm 30 which is pivoted as at 31 on travel arm 17, an adjustable abutment 32 being provided to normally maintain the pivot arm 30 substantially normal to the axis of movement of travel arm 17 against action of a spring 33 which connects pivot arm

30 with travel arm 17, as clearly shown in Fig. 2. The angularity of pivot arm 30 with respect to travel arm 17, however, may be adjusted by proper setting of the adjustment means 32.

The outer end of pivot arm 30 carries a threaded screw 34 (Fig. 2) which is adjustable in pivot arm 30 and secured in adjusted position by lock nut 35, the outer end of screw 34 normally contacting an abutment 36 (Fig. 7) at the rear end of feeding finger 10, a spring 37 connecting pivot arm 30 with abutment 36 so as to yieldably maintain the abutment 36 in contact with the free end of screw 34. By the above construction, in event the button blanks L in feed chute 11 should bind, or the lowermost blank L in the recess 10b of feeding finger 10 should bind, when the travel arm 17 is shifted to the right (Fig. 2) by engagement of the pivot arm 18 with the chuck spindle A, the pivot arm 30 would merely yield to the left (Fig. 2) in a counterclockwise direction, thereby shifting screw 34 away from the abutment 36 of the feeding finger 10 so that the feeding finger 10 would not be shifted to the right (Fig. 2) automatically by the movement of the chucks G approaching and leaving the feeding station. As soon, however, as the jam of blanks has been relieved, the feeding mechanism would automatically assume its proper working relation with the pivot arm 30 normally yieldably disposed at right angles to the axis of movement of travel arm 17, whereupon, as each chuck A approached the feeding station, the travel arm 17 would be shifted to the right (Fig. 2) by automatic engagement of the pivot arm 18 with the related chuck A; and upon each reciprocation of the travel arm 17 towards the right (Fig. 2) the lowermost button blank L would be forced by the feeding finger 10 to the right (Fig. 2) to deposit a button blank L in the underlying opened chuck G; and as soon as the forward end of pivot arm 18 engages the dog 22, the pivot arm 18 would be swung towards the travel arm 17, thereby disengaging the chuck with which it had previously been engaged, and the spring 21 will restore the parts to normal position so that the pivot arm 18 would be in position to be positively engaged by the next or following chuck spindle A in the row, so as to actuate the parts to insert the next or following button blank L in the next or following chuck G.

The feeder above described has been found to be very efficient in that it is impossible to feed more than one button blank L at a time by reason of the receding pin 12, and by reason of the action of the pivot arm 30 as a safety measure, which action eliminates the slipping of any clutches or breaking of parts in the button machine if the feeding stroke is jammed or impeded for any reason; and moreover, the provision of the pivot arm 30 and the receding pin 12 causes the mechanism to resume feeding in perfect register after any impeding jam or object is removed from the feeding path 11 of the blanks L, without any adjustment.

Power to operate the feeding finger 10 is picked up from the moving chuck spindles A by the pivot arm 18, which is attached to travel arm 17 causing the travel arm 17 to move forward in perfect register with the movement of chuck A until a button blank L is deposited in the same, after which the pivot arm 18 is tripped by contact against stationary dog 22, and all moving parts of the feeding mechanism are pulled back by the spring 21 into normal original position where same dwell long enough for the next blank L to be advanced from the end of feed chute 11 into position to be fed into the next chuck G; this cycle being repeated as each chuck G passes the feeding station.

The pivot arm 30 is normally held against a stop 32 on travel arm 17 by the spring 33, and pivot arm 30 transmits the stroke of travel arm 17 to the feeding finger 10 which pushes the blank L forwardly in perfect register with the chuck movement until the blank is dropped off the feed plate 1 under which the chuck is passing and

into the opened chuck G, but if, for any reason, normal movement of feeding finger 10 is impeded, the travel arm 17 continues its stroke cycle after cycle but the pivot arm 30 merely pivots on travel arm 17, stretching spring

5 33 during each stroke of travel arm 17 until the jam or foreign object is removed; then pivot arm 30 is again held by spring 33 against stop 32 on travel arm 17, and movement of the feeding finger 10 is resumed in perfect register with the chucks A without any readjustment on

10 the part of the operator or attendant.

The receding pin 12 is needed only to keep the blank L that is in position to be fed from rolling forward, or to the right (Fig. 2) after being positioned in the recess 10b of the feeding finger 10, as such forward movement 15 would allow the next blank in the feed chute 11 to advance prematurely; and pin 12 recedes from this position during the forward stroke of feeding finger 10 so as to clear the blank completely during the return stroke of feeding finger 10.

20 My feeding mechanism is adaptable for use in feeding plain or flat blanks, as well as blanks which are provided with integral shanks.

I do not limit my invention to the exact form shown in the drawings, for obviously changes may be made 25 therein within the scope of the claims.

I claim:

1. In combination with a button blank finishing machine having button holding chucks moving to and from a feeding station and having means at said station for 30 opening said chucks to receive therein button blanks respectively; a feed plate on said machine overlying said chucks above said station; a pair of spaced strips on said plate at opposite sides of the axis of movement of said chucks; a feed finger reciprocably mounted on said plate 35 between said strips, said finger having a recess in its side adapted to receive a button blank; a button blank feeding chute on said plate and adapted to feed blanks successively into the recess; a reciprocable travel arm carried by said plate parallel with the axis of movement of the chucks; 40 a pivot arm pivoted to the leading end of said travel arm; yieldable means for normally swinging the pivot arm into engagement with a chuck as the latter passes the feeding station; a fixed dog carried by said plate adapted to engage said pivot arm at the outward limit of travel of the travel arm and to swing the pivot arm out of engagement with said chuck; spring means for retracting the travel arm to normal position when the pivot arm is thus released into position to engage the next successive chuck; and a second pivot arm on the trailing end of said travel arm yieldably 45 connected with said feed finger for reciprocating the latter by and with the travel arm, said yieldable connection permitting the feed finger to remain inoperative in event of jamming of blanks at the feeding finger.

2. In a combination as set forth in claim 1, means for 50 adjusting the feeding plate transversely of the axis of movement of the chucks.

3. In a combination as set forth in claim 1, means for 55 initially maintaining a blank in said recess of the feed finger until the feed finger is shifted into position to drop the blank into the chuck.

4. In a combination as set forth in claim 1, a leaf 60 spring on the side of the feed finger disposed between the finger and one of said strips adjacent the leading end of the feed finger, said spring being adapted to bow outwardly from the finger when the finger approaches the outward limit of its travel; and a pin carried by the outer end of said spring and slidably in a bore disposed transversely of the feed finger in advance of the recess whereby when the finger is retracted the pin will maintain the 65 button blank confined in said recess until the pin is drawn outwardly of its bore by the forward movement of the feed finger.

5. In a combination as set forth in claim 1, an adjustable stop on said travel arm normally engaged by said 70 second pivot arm for maintaining same substantially nor-

mal to the travel arm; a second spring connecting the second pivot arm and travel arm for holding the second pivot arm against said stop; a threaded member adjustably carried by the outer end of said second pivot arm and normally engaging the trailing end of said feed finger, to normally shift the feed finger with said travel arm; and a third spring connecting the outer end of the second pivot arm and the said feed finger to yieldably maintain the threaded member in contact with said feed finger.

6. In a combination as set forth in claim 1, a guide rod carried by the outer end of the first pivot arm and adapted to engage the adjacent side of the chuck with which the pivot arm is engaged to limit the outward swinging movement of said first pivot arm by the action of said yieldable means.

7. In a combination as set forth in claim 1, a plate mounted on the tops of said strips above the feed finger; and a pin on said feeding finger slidable in a slot in said plate to limit the reciprocating movement of said feed finger.

8. In a combination as set forth in claim 7, and said plate having a transverse slot therein registering with the feed chute for permitting the lowermost button blank in the chute to enter the recess in the feed finger, the next adjacent blank in the chute being restrained from movement by engagement with the side of the feed finger when the latter is shifted towards feeding position.

9. In a combination as set forth in claim 1, said feed plate having a recess in its underside coaxial with the axis of movement of the chucks for permitting the chuck at the feeding station to rise thereunder into chuck opening position to receive a button blank.

10. In combination with a button blank finishing machine having an endless series of button holding chucks moving in an orbital path to and from a feeding station and having means at said station for opening said chucks to receive therein button blanks respectively; a feed plate mounted on said machine overlying said chucks above said station, said plate having a slot therein in its side in alignment with the axis of movement of said chucks; a pair of spaced strips on said plate at opposite sides of said slot; a feed finger reciprocably mounted on said plate between said pair of strips, said finger having a recess in its side adapted to receive a button blank; an inclined button blank feeding chute having its lower end secured on said plate and adapted to feed blanks successively into the recess of said finger; a travel arm reciprocably mounted on said machine parallel with and spaced from the axis of movement of the chucks at the feeding station; a pivot arm mounted at the leading end of said travel arm; yieldable means for normally swinging the pivot arm into engagement with a chuck as the latter passes the feeding station; a fixed dog on said machine adapted to engage said pivot arm at the outward limit of travel of the travel arm and to swing the pivot arm out of engagement with said chuck; spring means for retracting the travel arm to normal position when the pivot arm is thus released, into position to engage the next successive chuck; and a second pivot arm on the trailing end of said travel arm yieldably connected with said feed finger for reciprocating the latter by and with the travel arm, said yieldable connection permitting the feed finger to remain inoperative in event of jamming of blanks at the feeding finger.

11. A button feeding mechanism comprising a feed plate having a slot therein in its side; a pair of spaced strips on said plate at opposite sides of said slot; a feed finger reciprocably mounted on said plate between said

pair of strips, said finger having a recess in its side adapted to receive a button blank; an inclined button blank feeding chute having its lower end secured on said plate and adapted to feed blanks successively into the recess of said finger; a travel arm reciprocably carried by said plate; a pivot arm mounted at the leading end of said travel arm; yieldable means for normally swinging the pivot arm outwardly of said travel arm; a fixed dog carried by said plate adapted to engage said pivot arm at the outward limit of travel of the travel arm and to swing the pivot arm towards the travel arm; spring means for retracting the travel arm to normal position; to engage the next successive chuck; and a second pivot arm on the trailing end of said travel arm yieldably connected with said feed finger for reciprocating the latter by and with the travel arm, said yieldable connection permitting the feed finger to remain inoperative in event of jamming of blanks at the feeding finger.

12. In a mechanism as set forth in claim 11, means for initially maintaining the blank in said recess of the feed finger until the feed finger is shifted.

13. In mechanism as set forth in claim 11, a leaf spring on the side of the feed finger disposed between the finger and one of said strips adjacent the leading end of the feed finger, said spring being adapted to bow outwardly from the finger when the finger approaches the outward limit of its travel; and a pin carried by the outer end of said spring and slidable in a bore disposed transversely of the feed finger in advance of the recess whereby when the finger is retracted the pin will maintain the leading button blank confined in said recess until the pin is drawn outwardly of its bore by the forward movement of the feed finger.

14. In mechanism as set forth in claim 11, an adjustable stop on said travel arm normally engaged by said second pivot arm for maintaining said second pivot arm substantially normal to the travel arm; a spring connecting the second pivot arm and travel arm for holding the second pivot arm against said stop; a threaded member adjustably carried by the outer end of said second pivot arm, and normally engaging the trailing end of said feed finger to normally shift the feed finger with said travel arm; and a second spring connecting the outer end of the second pivot arm and the said feed finger to yieldably maintain the threaded member in contact with said feed finger.

15. In mechanism as set forth in claim 11, a plate mounted on the tops of said strips above the feed finger; and a pin on said feeding finger slidable in a slot in said plate to limit the reciprocating limits of said feed finger.

16. In mechanism as set forth in claim 15, and said plate having a transverse slot therein registering with the feed chute for permitting the lowermost button blank in the chuck to enter the recess in the feed finger, the next adjacent blank in the chute being restrained from movement by engagement with the side of the feed finger when the latter is shifted towards feeding position.
